UNITED STATES PATENT OFFICE

T. CLARENCE HEISEY, OF NEWARK, OHIO, ASSIGNOR TO A. H. HEISEY & COMPANY, OF NEWARK, OHIO

DESIGN FOR A FLOWER BOWL OR ARTICLE OF SIMILAR NATURE

Application filed March 29, 1930. Serial No. 35,068. Term of patent 14 years.

To all whom it may concern:

Be it known that I, T. CLARENCE HEISEY, a citizen of the United States, residing at Newark, in the county of Licking and State of Ohio, have invented a new, original, and ornamental Design for a Flower Bowl or Article of Similar Nature, of which the following is the specification, reference being had to the accompanying drawings, forming a part hereof.

I claim:

The ornamental design for a flower bowl or article of similar nature as shown.

T. CLARENCE HEISEY.
